ATTORNEY

UNITED STATES PATENT OFFICE.

JOHN WEBER, OF SCHENECTADY, NEW YORK, ASSIGNOR TO WEBER ELECTRIC COMPANY, OF SCHENECTADY, NEW YORK, A CORPORATION OF NEW YORK.

DESIGN FOR AN ATTACHMENT-PLUG CAP.

Application filed February 4, 1924. Serial No. 8,526. Term of patent 14 years.

To all whom it may concern:

Be it known that I, JOHN WEBER, a citizen of the United States, residing at Schenectady, in the county of Schenectady and State of New York, have invented a new, original, and ornamental Design for Attachment-Plug Caps, of which the following is a specification, reference being had to the accompanying drawing, forming part

Fig. 1 of the drawing is a top plan view of an attachment plug cap, showing my design.

Fig. 2 is a view in side elevation of the same.

I claim:

The ornamental design for an attachment plug cap, as shown.

JOHN WEBER.
